CLAIM

I claim the ornamental design for a hoistable harness, as shown and described.

DESCRIPTION

FIG. 1 is a perspective view of a hoistable harness embodiment showing our new design when in use;

FIG. 2 is a side view of the hoistable harness embodiment when in use;

FIG. 3 is an opposite side view of the hoistable harness embodiment when in use;

FIG. 4 is a top view of the hoistable harness embodiment when in use;

FIG. 5 is an end view of the hoistable harness embodiment when in use;

FIG. 6 is an opposite end view of the hoistable harness embodiment when in use;

FIG. 7 is a perspective view of the hoistable harness embodiment of FIG. 1 in a folded, configuration;

FIG. 8 is a top view of a hoistable harness embodiment of FIG. 1 in a folded, configuration;

FIG. 9 is a bottom view of the hoistable harness embodiment of FIG. 1 in a folded, configuration;

FIG. 10 is a top view of the hoistable harness embodiment of FIG. 1 in an open, laid-flat configuration; and,

FIG. 11 is a bottom view of the hoistable harness embodiment of FIG. 1 in an open, laid-flat configuration.

Broken lines or dotted sections in any of the foregoing Figures are for illustrative purposes only and form no part of the claimed design.

The hoistable harness shown in FIGS. 1-11 represent a single embodiment of the ornamental design of the article. The hoistable harness shown in FIGS. 1-5 depict the ornamental design aesthetics of the article when used for its intended purpose without any functionality implied or inferred. The hoistable harness shown in FIGS. 6-9 depict the ornamental design aesthetics of the folded article. e.g., before the article is used for its intended purpose, without any functionality implied or inferred. The hoistable harness shown in FIGS. 10-11 depict the ornamental design aesthetics of the article when used for its intended purpose, without any functionality implied or inferred.
